[57] CLAIM

The ornamental design for a combined goggle strap and ear covers, as shown and described.

DESCRIPTION

FIG. 1 is a rear elevational view of a combined goggle strap and ear covers showing our new design, the front view being identical with the omission of the hook and loop fastener patches;

FIG. 2 is a top plan view thereof, the bottom plan view being identical; and,

FIG. 3 is a left side elevational view thereof, the right side view being a mirror image.

FIG. 1

FIG. 2

FIG. 3
